UNITED STATES PATENT OFFICE.

JETHRO H. PECKHAM, OF PORTSMOUTH, RHODE ISLAND.

TORPEDO.

Application filed June 27, 1921. Serial No. 480,919.

To all whom it may concern:

Be it known that I, JETHRO H. PECKHAM, a citizen of the United States, residing at Portsmouth, Rhode Island, have invented 5 new and useful Improvements in Torpedoes, of which the following is a specification.

This invention relates to improvements in torpedoes and more particularly to the improvements in the steering mechanism 10 whereby the horizontal rudders are mechanically actuated to maintain the torpedo at the proper depth.

One of the objects of the present invention is to provide a simple and practical 15 mechanical means for controlling the horizontal steering means of a torpedo to the elimination of the air steering engine heretofore generally used.

A further object is to provide a device of 20 the above character of compact construction which may be easily installed in torpedoes now in use without material alteration or displacement of associated mechanisms.

A further object is to provide a mechanism 25 of the above character which will be largely automatic in its operation and so designed as to operate smoothly and efficiently under all conditions.

Other objects will be in part obvious and in 30 part hereinafter pointed out in connection with the accompanying sheet of drawing forming part of this disclosure wherein Figures 1 and 2 are elevation views of such parts of the mechanism as are necessary to 35 understand the invention, taken at right angles to each other.

Figure 3 is a sectional view taken substantially on the line 3/3, Figure 1.

Figure 4 is a sectional view taken substantially on the line 4/4, Figure 1.

Figure 5 is a sectional view taken substantially on the line 5/5, Figure 1.

Referring now to the drawings in detail and more particularly to Figures 1 and 2, a 45 main base or frame 5 which is interchangeable with a standard steering engine bracket now in use in torpedoes, supports a shaft 6 shown in Figure 5 provided with a gear 7 meshing with the usual distance gear 8 as shown in Figure 3. The distance gear is mounted on the outer propeller shaft and is adapted to drive the pallet as hereinafter more fully explained. The other end of the shaft 6 is provided with an eccentric 10 as 50 shown in Figure 4 for causing a pallet 11 associated therewith to oscillate in a vertical

plane. This pallet carries a pawl 12 pivotally mounted thereon by means of stud 13 and is connected by means of a second stud 14 with a pilot rod 15 connected to the standard linkage well known to those skilled in the art and motion is transmitted from the pendulum and hydrostatic mechanism, not shown, to this steering device. A spring take-up 16 is provided in the rod 15 to absorb excess motion of the connecting linkage over that required to properly engage the pawl 12 with either of two eccentric circular cams 17 and 18 provided with ratchet teeth as shown extending along the major part of 60 their surface said ratchet teeth being cut on a circular face eccentric with the center of revolution. These cams 17 and 18 convert the oscillatory movement of the pallet 12 into circular motion in either direction. For this 65 purpose they are geared together by bevel gears 20 mounted upon shaft 21. Motion is transmitted to the rudder rod by means of link 22 carrying a block 23 meshing with worm 24, this worm being pinned to the 70 shaft 21 and is revolved in either direction by the circular cams 17 and 18 and the bevel gears 20. The link 22 and shaft 21 are provided with suitable bearings in a frame 25 secured to the main frame 5. 75

The operation of the present device is briefly stated as follows:—Assuming that the torpedo has taken a dive, the pendulum will swing forward carrying the pilot rod 15 aft a certain amount, proportionate to 80 the angle of dive thus causing the pawl 12 to engage in the steps or ratchet surface of the circular cam 17 and as it reciprocates cause this cam 17 to revolve in the direction of the arrow as shown. This movement revolves the shaft 21 and causes the worm 24 and rack or block 23 to move the link 22 aft and thus give the horizontal rudders an 85 "up" position. As the face of the cam 17 is eccentric with its center of rotation, as 90 it is rotated, the face retreats until it has moved longitudinally an equal amount with the throw of the pallet, at which position the pawl 12 will free itself of the cam and idle between the two cams until an additional or 95 counter impulse is received at which time the motion is continued or reversed. The worm and rack drive serve as a lock to hold the link 22 in any position against outside pressure. 100

It will thus be seen that the present invention provides a simple, practical and 110

reliable mechanism adapted to control the position of the horizontal steering rudder under all conditions.

Without further analysis, the foregoing will so fully reveal the gist of this invention that others can by applying current knowledge readily adapt it for various applications without omitting certain features that, from the standpoint of the prior art, fairly 10 constitute essential characteristics of the generic or specific aspects of this invention and, therefore, such adaptations should and are intended to be comprehended within the meaning and range of equivalency of the 15 following claims.

What I claim is:—

1. In a mechanism of the character described, in combination, a main shaft, a pallet actuated thereby, cams associated with 20 said pallet and adapted to be connected with the horizontal rudder, and means for bringing said pallet into engagement with one or the other of said cams to operate said rudder.
2. In a mechanism of the character described, in combination, a main shaft, a pallet actuated thereby, cams associated with 30 said pallet adapted to be connected with the horizontal rudder, means for bringing said pallet into engagement with one or the other of said cams to operate said rudder, said means comprising a link adapted to be connected with the depth control mechanism, a rack and worm, and gearing for 35 actuating said rack and worm.
3. In a mechanism of the character de-

scribed, in combination, a shaft adapted to be rotated by the distance gear, a pallet eccentrically connected with said shaft, cams adapted to be engaged by said pallet, said 40 cams adapted to be rotated a variable amount, a link adapted to be connected with the horizontal steering rudder, and means for causing said link to be moved in one direction or the other a variable amount according to which cam is engaged with said pallet.

4. In a mechanism of the character described, in combination, a shaft adapted to be rotated by the distance gear, a pallet eccentrically connected with said shaft, cams adapted to be engaged by said pallet, a link adapted to be connected with the horizontal steering rudder, and means for causing said link to be moved in one direction or the other 50 according to which of said cams is engaged with said pallet.

5. In a mechanism of the character described, in combination, a shaft adapted to be rotated by the distance gear, a link 60 adapted to be connected with the horizontal rudder and mechanical means interposed between said shaft and link for causing the link to be moved in one direction or the other, said means comprising a reciprocating pallet, cams adapted to be engaged by 65 said pallet and gearing interposed between the cams and the link for transmitting motion to the link as the cams are engaged.

Signed at Newport, R. I. this 31 day of 70
March, 1921.

JETHRO H. PECKHAM.
